UNITED STATES PATENT OFFICE

2,664,472

AUTOMATIC ELECTRIC FROG

Everett C. Brown, Louisville, Ky., and Thomas Finan, Providence, R. I., assignors to Cheatham Electric Switching Device Company, Incorporated, Louisville, Ky., a corporation of Kentucky

Application September 8, 1950, Serial No. 183,874

6 Claims. (Cl. 191—38)

1

This invention relates to the operation of dirigible and track vehicles that are propelled by electricity received from overhead positive and negative trolley wires through trolley collectors carried by such vehicles and has particular application to trolley-bus systems wherein a "turn-out" is to be effected through the selection and operation of a frog tongue or tongues for guiding current collectors from through or main trolley wires on to branch wires in response to the longitudinal relation of one trolley collector to the other which occurs when making the turn-out and to where the trolley collectors are oppositely disposed as when the trolley-bus is proceeding on the straight line of travel. In turn-out operations of this class, it has been learned that the longitudinal relative displacement of the trolley shoes is not always sufficiently pronounced or definite to be depended upon, consequently, many efforts have been made to overcome this condition. Such efforts have resulted in what now may be appraised as unnecessarily involved electrical and mechanical apparatus. An illustration of such a device is found in Patent No. 2,268,922 issued January 6, 1942 to one of the instant co-inventors. The following patents, directed to the solution of this problem disclose involved and complex electrical and/or mechanical apparatus when compared with that disclosed herein: 2,235,961, March 25, 1941; 2,264,839, December 2, 1941; 2,292,820, August 11, 1942 and 2,299,914, October 27, 1942. Although the designated systems have been produced, installed and used, each has been found wanting in some respect or respects.

The main object of our invention is to eliminate the inherent disadvantages that have been found in previous systems of this class and to provide a system that will operate through long periods of time with the desired definiteness.

Another object is to provide simplified apparatus for the type of operation referred to above that can be produced and delivered to the operating companies at a relatively low cost.

A further object of our invention is to provide automatic electrically operated frogs that are relatively easy to install and maintain for long periods of service without attention.

Other objects, advantages and features may appear from the accompanying drawings, the subjoined detailed description and appended claims.

In the drawings:

Figure 1 is a schematic illustration of the apparatus and control system for our automatic

2

electrically-operated frogs embodying the invention disclosed herein to explain the operation thereof when the current collectors carried by a trolley-bus are on the verge of changing their course of travel from the main or through wires to branch wires.

Figure 2 is similar to Figure 1, however, modified to disclose the operation of certain elements that prevent operation of the tongues of the frogs when the trolley-bus precedes on the straight through course of travel.

Figure 3 is an enlarged view of the type of contact device indicated in schematic illustration of the apparatus and control system in Figs. 1 and 2.

Referring now in particular to Figure 1, it will be observed that the system includes main line and branch line positive and negative current conductors or wires designated respectively by characters P, P₁; N, N₁ and that they are engaged respectively by current collectors 5, 6 of a trolley-bus, not shown. Numerals 7, 8 designate movable tongues at the turn-out point to provide a definite path of travel for the collectors along the main line or to the branch line. Springs S are arranged to bias normally the tongues for the collectors to traverse the main line of travel. Obviously, the tongues can be reversed so that the normal or rest position will be for the turn-out course of travel by using the springs oppositely to that illustrated. Operatively attached to these tongues are plungers designated respectively 7A, 8A that are operated by normally deenergized electromagnets 7M, 8M, the solenoids of which are designated by 7S, 8S.

Adjacent the tongue of each frog is a contact device comprising swingable arm 10 located for movement by a current collector and pivoted in bearing 11 mounted on a wire by perch 12. The free end 13 of each arm, when operated by a collector from the rest position, as shown in Figure 1 adjacent the negative wire, has been moved to the operated position, whereupon it engages and moves bell-crank 14 from one contact to the other. The bell-cranks are pivoted in bearing 15 which are mounted on perches 16 attached and electrically connected to wire N or P. Each bell-crank is the mechanical actuator of the selector switch for the circuit that is to apply current to a solenoid for moving the tongue operatively associated therewith and to interrupt the circuit to prevent operation of the solenoid on the other wire.

The circuits and actuator in both figures are identical, and are organized so that only one

frog can be operated at a given time, incident to one passage of the trolley-bus collectors through the system, when making a turn-out, however, incident to each through passage both contact devices are operated simultaneously and the circuits rendered deenergized.

In the system as shown in Figure 1, the positive wire contact device, as set, feeds current through wire 20, bell-crank 14P, wire 24, solenoid 8S, wire 22, bell-crank 14N, wire 23 to the negative wire, thereby pulling plunger 8A and its associated tongue from the straight line course of travel to the branch line of travel. It should be noted that bell-crank 14N has been moved from the rest position to the position as shown by current collector 6, and that this collector has engaged and overlapped one of the tongues of the associated frog while arm 10 remains raised for operating the said bell-crank thereby closing the circuit referred to above, after which operation it is returned to normal by the spring, SN. This condition continues until the collector has passed from arm 10. Immediately following this operation, collector 5 will likewise operate bell-crank 14P, as shown in Figure 2, whereupon current flows from the positive wire to wire 20, bell-crank 14P, wire 24, solenoid 7S, wire 25, bell-crank 14N, wire 23, to the negative wire whereupon plunger 7A responds to the magnetic force and moves the tongue in the positive wire line so that the collector will then travel upon branch wire P1. After both collectors have passed from arms 10, the bell-cranks will be returned to the rest position by their related springs as stated above. It should be observed that while one solenoid is energized the circuit for the other solenoid has been opened.

During the straight through course of travel, as shown in Figure 2, both arms 10 have actuated the bell-cranks from the rest position. This operation opens the circuits of both solenoids as will be noted from the following: beginning with the positive wire; wire 20, bell-crank 14P, wire 24, solenoid 7S, and wire 25 to an open switch. Beginning with the negative wire the circuit includes wire 26, bell-crank 14N, wire 22, solenoid 8S, wire 25 to an open switch. Since both these circuits are opened, as adverted to above, both solenoids will be inactive and the tongues remain in the rest position through the influence of spring S and that after the current collectors have passed from arms 10 the bell-cranks will return to their respective rest positions and re-establish the circuits to normal state.

Bell-crank 14P in Figure 1 is shown in the rest position under influence of spring SP, while bell-crank 14N is shown in the operated position against spring SN.

The physical embodiment of our invention as disclosed herein is the form presently in commerce. Manifestly, the invention as illustrated and described is susceptible of modification without departing from the inventive concept, and right is hereby reserved to such modifications as fall within the scope of the appended claims.

We claim:

1. In a switching system for a pair of current collectors mounted on a vehicle, a pair of main trolley wires of opposite polarity and a branch wire for each main wire, a trolley frog at the intersection of each main and branch wire, to guide a current collector on the vehicle either along the main wire or on to the branch wire, each frog provided with a movable tongue forming the guiding means for said current collectors,

yielding means for biasing each tongue for a selected position for guiding a current collector along the main wire, a solenoid for operating a mechanism for moving each tongue for guiding a current collector from the main wire to the branch wire, control means for energizing said solenoid of each of said mechanisms comprising a contact device located adjacent each tongue and operated by a current collector so that each of said current collectors will retain the contact devices associated therewith in the operated position until the incident operating collector has engaged the tongue associated therewith.

2. In a switching system for a pair of current collectors mounted on a vehicle, a pair of main trolley wires of opposite polarity and a branch wire for each main wire, a trolley frog at the intersection of each main and branch wire to guide a current collector on the vehicle either along the main wire or on to the branch wire, each frog provided with a movable tongue forming the guiding means for said current collectors, yielding means for biasing each tongue for a selected position for guiding a current collector along one course of travel, electrically operated mechanism for moving each tongue for guiding a current collector to the other course of travel, control means for energizing the solenoid of each of said mechanisms comprising an electrical contact device located adjacent each tongue and operated by a current collector so that each of said current collectors will retain the contact devices associated therewith in the operated position until the incident operating collector has engaged the tongue associated therewith.

3. In a switching system for a pair of current collectors mounted on a vehicle, a pair of main trolley wires of opposite polarity and a branch wire for each main wire, a trolley frog at the intersection of each main and branch wire to guide a current collector on the vehicle either along the main wire or on to the branch wire, each frog provided with a movable tongue forming the guiding means for said current collectors, yielding means for biasing each tongue for a selected position for guiding a current collector along the main wire, electrically operated mechanism for moving each tongue for guiding a current collector from the main wire to the branch wire, control means for energizing the solenoid of each of said mechanisms comprising a contact device located adjacent each tongue and operated by a current collector so that each of said current collectors will retain the contact devices associated therewith in the operated position until the incident operating collector has engaged the tongue associated therewith; each of said contact devices having a selector switch operatively associated therewith for permitting and interrupting current flow to each solenoid.

4. In a switching system for a pair of current collectors mounted on a vehicle, a pair of main trolley wires of opposite polarity and a branch wire for each main wire, a trolley frog at the intersection of each main and branch wire to guide a current collector on the vehicle either along the main wire or on to the branch wire, each frog provided with a movable tongue forming the guiding means for said current collectors, yielding means for biasing each tongue for a selected position for guiding a current collector along the main wire, electrically operated mechanism for moving each tongue for guiding a current collector from the main wire to the branch wire, control means for energizing the

solenoid of each of said mechanisms comprising a contact device located adjacent each tongue and operated by a current collector so that each of said current collectors will retain the contact devices associated therewith in the operated position until the incident operating collector has engaged the tongue associated therewith; each of said contact devices having a selector switch operatively associated therewith for permitting and interrupting current flow to each solenoid; said contact devices located so that both will be operated to prevent current flow to both solenoids when engaged simultaneously by said collectors.

5. In a switching system for a pair of current collectors mounted on a vehicle, a pair of main trolley wires of opposite polarity and a branch wire for each main wire, a trolley frog at the intersection of each main and branch wire to guide a current collector on the vehicle either along the main wire or on to the branch wire, each frog provided with a movable tongue forming the guiding means for said current collectors, yielding means for biasing each tongue for a selected position for guiding a current collector along the main wire, electrically operated mechanism for moving each tongue for guiding a current collector from the main wire to the branch wire, control means for energizing the solenoid of each of said mechanisms comprising a contact device located adjacent each tongue and operated by a current collector so that each of said current collectors will retain the contact devices associated therewith in the operated position until the incident operating collector has engaged the tongue associated therewith; each of said contact devices having a selector switch operatively associated therewith for permitting current flow to one of said solenoids and preventing current flow to the other solenoid.

6. In a switching system for a pair of current

collectors mounted on a vehicle, a pair of main trolley wires of opposite polarity and a branch wire for each main wire, a trolley frog at the intersection of each main and branch wire to guide a current collector on the vehicle either along the main wire or on to the branch wire, each frog provided with a movable tongue forming the guiding means for said current collectors, yielding means for biasing each tongue for a selected position for guiding a current collector along the main wire, electrically operated mechanism for moving each tongue for guiding a current collector from the main wire to the branch wire, control means for energizing the solenoid of each of said mechanisms comprising a contact device located adjacent each tongue and operated by a current collector so that each of said current collectors will retain the contact devices associated therewith in the operated position until the incident operating collector has engaged the tongue associated therewith; each of said contact devices having a selector switch operatively associated therewith for permitting current flow to one of said solenoids and preventing current flow to the other solenoid; said contact devices located so that they will be operated sequentially by the collectors on a vehicle when carried by a vehicle as it leaves a main course of travel for the branch course of travel.
